UNITED STATES PATENT OFFICE.

FRANK R. BATCHELDER, OF WORCESTER, MASSACHUSETTS.

POCKETED CARRIER.

1,340,141.

Specification of Letters Patent.

Patented May 18, 1920.

Application filed September 25, 1918. Serial No. 255,563.

To all whom it may concern:

Be it known that I, FRANK R. BATCHELDER, a citizen of the United States, residing at Worcester, in the county of Worcester,

5 State of Massachusetts, have invented a certain new and useful Improvement in Pocketed Carriers, of which the following is a specification, reference being had therein to the accompanying drawings.

10 The invention has relation in general to pocketed carriers on the order of those which are used for holding and carrying cartridges, packaged first-aid supplies, etc. Among the pocketed carriers to which the 15 invention is applicable are comprised cartridge-carriers, hospital corps belts, medical officers' belts, and others having various special adaptations.

The pockets of woven carriers as ordinarily produced taper and diminish in size toward their closed bottoms, so that their lower portions are of less internal capacity than the upper portions. This is unavoidable when the pockets are woven according 25 to usual methods. It is a more or less inconvenient drawback in many cases, and prevents the employment of the pockets for various important purposes. So, also, when the pockets are constructed with internal 30 reinforcements or linings extending part way up the front walls thereof, such reinforcements or linings reduce the internal capacity of the lower portions of the pockets as compared with that of the upper portions. 35 With the reduction due to the reinforcements or linings added to the contraction of the lower portions of the pockets, a material difference in internal capacity exists between the upper and lower portions 40 of the pockets.

The object of the invention is to avoid the foregoing drawback.

The invention provides pockets having increased internal capacity in their bottom 45 portions.

Embodiments of the features of the invention are illustrated in the drawings, in which latter,—

Figure 1 is an isometric of a portion of a 50 pocketed carrier having pockets embodying the invention, one of such pockets being presented in vertical section.

Fig. 2 is an isometric of a single pocket which is shown in vertical section and without its cover-flap, this view illustrating the 55 infold of the pocket-bottom.

Figs. 3 and 4 are diagrams illustrating one mode of weaving the pockets of Figs. 1 and 2.

Having reference to the drawings,— 60

Fig. 1 shows a portion of a multiple-pocketed carrier. The invention may be utilized in the manufacture of carriers having in their finished state a series of pockets connected together as in Fig. 1, or in that 65 of those having or consisting of individual pockets. As produced in a loom the pockets 1, 1, are woven side by side as portions of a continuous carrier-web, they being joined together in the said web by band-portions 70 2, 2, which are formed intermediate and at opposite sides of the respective pockets. After the weaving of the carrier-web, it is divided up by cutting across the same 75 through the said band-portions 2, 2, into sections comprising respectively the required number of pockets. Cover-flaps on the order of those represented at 4, 4, Fig. 1, customarily are provided in connection with the pockets. The upper end of the right-hand cover-flap in Fig. 1 is represented as broken away, for want of space in which to show the same.

The pockets of carriers are reinforced internally in various ways in practice to enable them to withstand better the wear due to their contents. Reinforcement is essential in the case of cartridge-carriers, especially. Fig. 1 shows a well-known mode of reinforcing in which a downward prolongation of the cover-flap lines the back and bottom of the pocket, and the lower part of the upright portion of the pouch thereof. 90

The gist of the invention consists in 95 avoiding the fault aforesaid, namely, smaller internal capacity of the lower portion of the pouch of a carrier-pocket as compared with that of the upper portion thereof, by giving the said lower portion relatively increased dimensions in weaving the pouch. 100 Figs. 1 and 2 show the pockets, which are woven seamless according to methods of well-known general characters, as woven larger in horizontal cross-section in their 105 lower portions 1^a, 1^a, than above the said portions. Thus the said increase of capacity is secured, and when a pocket is furnished with a reinforcement or lining the upright portion of the latter, in this instance the upturn 4^a of the lining, is accommodated without reduction of the contain- 110

ing capacity of the lower portion of a pocket below that of the upper portion of the pocket.

The invention may be embodied in the pockets of carrier-webs in various ways involving in substance the formation of the pouches of said pockets of downwardly divergent weave. The drawings illustrate one convenient and practicable way, it consisting in incorporating additional picks of weft in the lower portion of the pouch of a pocket, so that the length or measurement of said portion of the pouch from the pocket-back horizontally around the side-walls and front wall of the pouch to the pocket-back again will be greater in the said lower portion than in the case of the upper portion of the pocket. These additional picks are indicated at *a*, *a*, in Figs. 3 and 4. Fig. 3 is a diagram of open or skeleton character showing side by side the wefting of the pocket at different points in a pocket. It shows the four different arrangements of picks that are utilized at different points in Fig. 4. The warp-threads which in the actual pocket are interwoven with the weft or filling are not shown. In Fig. 3, the approximately vertical position of the pocket-back, the approximately horizontal position of the pocket-bottom, the general character of the fold in which it is woven, and the vertical position of the wall of the pouch, are indicated. In such figure, also, the pouch-wall and back are shown somewhat widely separated from each other, with the bottom-fold flattened nearly down, and the successive picks of weft are shown separated widely, in order to indicate the general plan of the wefting more clearly. In Fig. 4 all the picks of weft are developed in one plane.

A sufficient number of the additional picks, *a*, *a*, is incorporated in the lower portion of the pouch to give the desired result. It will be apparent that the incorporation of the said additional picks in the said portion will render the length of the latter around the sides and front of the pouch greater than the length around the upper portion of the pouch.

The invention is shown embodied in a pocket having a bottom woven of bellows-bottom formation, the infold of which is indicated in Figs. 2, 3, and 4, but is flattened out in Fig. 1. This form of bottom permits the bottom of the pocket to spread forward away from the pocket-back.

Referring to the wefting in general, the

number of picks *b*, *b*, of weft or filling contained normally in the pouch-wall of a pocket is considerably larger than the number of picks *c*, *c*, contained in the pocket-back, in order to give the required bulge and fullness to the pouch. The preponderance is indicated in Figs. 3 and 4. As has been stated, the short picks *a*, *a*, occupying only the lower portion of the pouch-wall are added in conformity with the invention. The front side of the bottom fold contains usually a less number of picks *d*, *d*, of weft than the pouch-wall, as indicated, and the rear side of said fold contains usually a smaller number of picks *e*, *e*, than the said front side, as indicated. By way of suitably proportioning the pocket-bottom to the relatively-increased dimensions of the lower portion of the pouch, I incorporate additional picks *d'*, *d'*, at suitable intervals in the front side of the bottom-fold, and additional picks *e'* at suitable intervals in the rear side of the said fold.

The invention is not necessarily restricted to the herein described mode of securing the downwardly-divergent weave of the pouch-wall.

What is claimed as the invention is:—

1. A lined woven carrier-pocket having the portion thereof which is occupied by the upturn of the lining relatively larger horizontally than the portion not thus occupied.

2. A woven carrier-pocket having the bottom and lower portion of its front reinforced, and also having the said portion larger than the portion above it, to accommodate the upright portion of the reinforcement without reduction of the containing capacity of the said lower portion.

3. A pocketed carrier comprising a belt portion, and a plurality of seamless carrier-pockets, each of said pockets having the upright portion thereof woven larger in horizontal cross-section in its lower portion than above the said portion.

4. A pocketed carrier comprising a belt portion, and a plurality of pockets, each of said pockets having the vertical portion of the pouch thereof of downwardly divergent weave whereby increase of capacity in the lower portion of the said pouch is attained.

In testimony whereof I affix my signature in presence of two witnesses.

FRANK R. BATCHELDER.
